UNITED STATES PATENT OFFICE

3,386,215

BOAT

Harold B. Harvey, Pensacola, Fla.

Application May 19, 1944, Serial No. 536,362

1 Claim. (Cl. 115—19)

The present invention relates to new and useful improvements in boats, and has for its primary object to provide a vehicle of this character comprising propelling means of a unique construction and arrangement.

Another very important object of the invention is to provide a boat of the character described comprising a hull of novel shape whereby water and wind resistance will be reduced to a minimum.

Other objects of the invention are to provide a boat of the character set forth which will be comparatively simple in construction, strong, durable, seaworthy, attractive in appearance and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a top plan view of a boat constructed in accordance with the present invention.

Figure 2 is a view in side elevation thereof with the rear end portion of the propeller broken away.

Figure 3 is a view in bottom plan of the boat.

Figure 4 is a view in longitudinal section through the propelling means, taken substantially on the line 4—4 of Figure 1.

Figure 5 is a view in transverse section, taken substantially on the line 5—5 of Figure 1.

Figure 6 is a view in transverse section, taken substantially on the line 6—6 of Figure 4.

Figure 7 is an enlarged fragmentary view in transverse section, taken substantially on the line 1—7 of Figure 4.

Referring now to the drawings in detail, it will be seen that the embodiment of the invention which has been illustrated comprises a hull of suitable dimensions and material which is designated generally by reference character 1. The hull 1 includes a bottom 2 of substantially the shape shown to advantage in Figures 3 and 5 of the drawings.

Extending longitudinally into the hull 1 from the stern thereof is a recess 3. Thus, the stern portion of the hull 1 is divided into what may be considered a pair of spaced, parallel stabilizers 4. The bottoms of the stabilizers 4 are stepped, as at 5.

A cabin 6 is provided in the hull 1 forwardly of the recess 3. The cabin 6 rises above the deck 7 of the hull 1. Fixed on the transom 8 which extends between the stabilizers 4 at the rear of the cabin 6 is a substantially bullet-shaped, stationary inner shell 9. A suitable engine 10 is mounted in the shell 9. Mounted centrally in the shell 9 is a longitudinal propeller shaft 11. The rear end portion of the shaft 11 extends through a suitable bearing 12 which is provided

therefor on the rear end portion or nose 13 of the shell 9. In the embodiment shown, the forward end portion of the shaft 11 is journaled in a bearing 14 on the engine 10. The engine 10 drives the shaft 11 through a belt and pulley connection 15.

Mounted on the shell 9 is a propeller which is designated generally by reference character 16. The propeller 16 includes a substantially bullet-shaped, rotary outer shell 17 which encloses the stationary inner shell 9 in spaced relation thereto. Suitable bearings 18 are provided for the outer shell 17. Fixed on the outer shell 17 and extending substantially from end to end thereof is a spiral fin or blade 19.

A drive connection 20 is provided between the shaft 11 and the propeller 16. This connection includes an internally toothed ring 21 which is fixed in the nose portion 22 of the shell 17. Fixed on the rear end portion of the shaft 11 is a gear 23 which is meshed with the teeth of the ring 21.

It is thought that the operation of the boat will be readily apparent from a consideration of the foregoing. Briefly, the power plant 10 rotates the propeller 16 on the stationary inner shell 9 through the belt and pulley drive 15, the shaft 11 and the connection 20. Thus, the substantially spiral fin or blade 19 is caused to turn in the water and simply function substantially in the manner of an auger for propelling the boat. A continuous "bite" is had in the water from end to end of the fin or blade 19. The engine 10 may be controlled from the cabin 6 in any desired manner. Also, any suitable means may be provided for steering the boat.

It is believed that the many advantages of a boat constructed in accordance with the present invention will be readily understood, and although a preferred embodiment of the boat is as illustrated and described, it is to be understood that changes in the details of construction and in the combination and arrangement of parts may be resorted to which will fall within the scope of the invention as claimed.

45 What is claimed is:

A boat comprising a hull having a recess extending longitudinally thereinto from the rear end thereof and providing a pair of spaced, parallel, rearwardly extending stabilizers, a cabin in the hull forwardly of the recess, a transom extending between the stabilizers and constituting the rear wall of the cabin, an elongated, stationary inner shell fixed on the transom and communicating with the cabin, said inner shell extending rearwardly in the recess between the stabilizers, a power plant in the inner shell, an outer shell rotatable on the inner shell, a spiral blade on said outer shell, and means operatively connecting the power plant to the outer shell for propelling the boat.

HAROLD B. HARVEY.
